UNITED STATES PATENT OFFICE.

FREDERICK THEODORE MAY, OF MONTCLAIR, NEW JERSEY, ASSIGNOR TO WESTINGHOUSE LAMP COMPANY, A CORPORATION OF PENNSYLVANIA.

DESIGN FOR AN ELECTRON-EMISSION DEVICE.

Application filed October 7, 1927. Serial No 23,664. Term of patent 14 years.

To all whom it may concern:

Be it known that I, FREDERICK THEODORE MAY, a citizen of the United States, residing in Montclair, in the county of Essex and State of New Jersey, have invented a new, original, and ornamental Design for an Electron-Emission Device, of which the following is a specification, reference being had to the ac-

companying drawing, forming part thereof.

Fig. 1 is a top or plan view of the device; and,

Fig. 2 is a side elevational view thereof.

I claim:

The ornamental design for an electron emission device as shown.

FREDERICK THEODORE MAY.
